UNITED STATES PATENT OFFICE.

FRANK DE WITTE JACOBS, OF EL CENTRO, CALIFORNIA.

METAL BINDING STRIP.

Application filed December 10, 1924. Serial No. 755,094.

To all whom it may concern:

Be it known that I, FRANK DE WITTE JACOBS, a citizen of the United States, and resident of El Centro, in the county of Imperial and State of California, have invented certain new and useful Improvements in Metal Binding Strips, of which the following is a specification.

My invention is a metal binding strip for use in securing a piece of foraminous, wire or other sheet material, upholstering fabric or the like to a frame or like support, and it consists in the combinations, constructions and arrangements herein described and claimed.

An object of the invention is the provision of a metal binding strip which affords facilities for securing wire or other fabric to a frame or like support so that the fabric will be effectively prevented from slipping or sagging from a desirable position in respect to the frame or like support.

A further object of the invention is the provision of a metal binding strip which can be quickly and easily applied to a frame for the purpose of securing fabric to the frame.

A further object of the invention is the provision of a metal binding strip of the character described which when in applied position on a screen or like frame serves not only to attach wire or other fabric to the frame in the manner of nails or like attaching devices but also serves to clamp the fabric to the frame in the manner of the usual strip of molding.

Other objects and advantages will be apparent from the following description, considered in conjunction with the accompanying drawings, in which—

Figure 1 is a fragmentary perspective view showing a metal strip embodying the invention in position to secure a wire fabric to a frame member.

Figure 2 is a plan view of the metal strip disposed with the fastening projections thereof uppermost.

Figure 3 is a side elevation of the metal binding strip.

Figure 4 is a section along the line 4—4 of Figure 2.

Figure 5 is a fragmentary vertical section through a frame member, a piece of wire fabric, and a modified form of binding strip in position to secure the piece of fabric to the frame member.

As is well known, wire or other fabric ordinarily is secured to a wooden frame or like support by means of tacks which are driven through the fabric at intervals along the support to attach the fabric to the support. A piece of fabric so attached to a support will sag between adjacent nails or like fastening devices and a piece of fabric so attached to the support is very readily torn loose from the support, particularly when the tacks have been driven through the fabric adjacent to an edge thereof. It has been customary prior to my invention to make use of strips of molding in conjunction with the tacks or like fastening devices to secure fabric in place on a frame or to a like support, the molding being tacked to the frame or like support over the heads of the tacks and serving to aid the tacks in holding the fabric in place. My invention provides a strip which combines in one member projections adapted to be driven through fabric into a frame member or like support and an elongated body which carries the projections and will be in position when the projections have been driven into the frame member or like support to clamp the fabric to the frame member or like support in somewhat the same manner as a strip of molding, such as it has been the usual practice to provide prior to my invention. However, the projections and the binding body of the strips which my invention provides obviously will more effectively secure the fabric to a screen frame (or like support) so that the fabric is not permitted to sag or stretch between the members of the screen frame or like support than is possible with the use of separate parts and molding strips, as will be understood from the following description.

A metal binding strip embodying the invention as illustrated in Figures 1 to 4 inclusive is formed of a strip of metal having substantially parallel longitudinal edges, such strip being folded along lines which

extend longitudinally of the strip, the folded over portions of the strip being bent outwardly along lines which extend longitudinally of the strip approximately midway of the width of the folded over portions until such outturned edge portions lie in planes extending at right angles to the body of the strip. The outturned edge portions are indicated at 2, and are serrated by notches in the edges thereof, thus producing rows of substantially V-shaped projections, the projections of the respective rows being arranged in staggered relation. The body of the strip is provided at intervals along its length and midway of its width with openings 3 for the reception of nails, as at 4, or like fastening devices, whereby the body of the strip will be clamped closely against a support 5, which may be a rail member of a frame for supporting a sheet of wire fabric 6, when the fastening projections 2 of the strip have been projected through the fabric into the support 5 until the body of the strip presses the underlying portion of the fabric flatwise against the support. In actual practice, the fastening projections 2 will be formed to be approximately the same size at their bases as the openings of a sheet of wire fabric through which they will be projected, whereby the wires which define the openings of the wire fabric will be firmly clamped between the body of the strip and the support into which the projections have been driven, whereby the fabric will be held securely against sagging or slipping from a desired position in respect to the support.

In the form of the device exhibited in Fig. 5, an elongated strip 10 of metal is bent along lines extending longitudinally thereof to provide a pair of inwardly extending aligned flanges 11 which connect and merge the longitudinal edge portions of the strip with and in to the body thereof. The outturned end portions of the strip 2 extend at right angles to the flanges 11 and are serrated to provide the rows of pointed teeth as in the case of the form of the strip which is illustrated in Figures 1 to 4 inclusive and has been hereinbefore described. The body of the strip 10 is curved arcuately between the line of its juncture with the flanges or connecting portions 11. A space thus is defined between the inner walls of the connecting portions 11 and the remaining portion of the body of the strip. This space may be filled by a filler member 12.

The operation of the form of the device exhibited in Figure 5 is identical in essential respects with that of the form of the device exhibited in Figures 1 to 4 inclusive and is thought to require no description herein.

While each of the embodiments which I have illustrated and described is formed

to provide two parallel rows of substantially V-shaped fastening projections, it will be obvious that a greater or less number of rows of fastening projections may be provided on the body of the strip without departing from the spirit and scope of the invention. Moreover, the pointed projections 2 may be formed in any suitable known manner from a strip of metal, may be spaced apart as desired and may have any desirable length within a considerable range and be of any desirable configuration in cross sectional contour to meet particular conditions. When two or more rows of pointed projections are provided on the body of the strip, the respective projections of adjacent rows need not be disposed in staggered relation as shown in the drawings but corresponding projections can be disposed in transverse alignment with each other. The material of which the strips and projections on the body thereof is formed should be of material possessing sufficient rigidity to prevent individual projections from turning laterally under the impact of a blow on the outer face of the body of the strip for the purpose of driving the projection into a frame member or like support.

The outer face of the body of the strip may be ornamented in any suitable known manner to adapt the strip for use in upholstering work in which an ornamental strip is desired.

Obviously, my invention is susceptible of embodiment in forms other than those illustrated in the accompanying drawings and I therefore consider as my own all such modifications and adaptations of the forms of the device herein described as fairly fall within the scope of the appended claims.

I claim:

1. A metal binding strip formed of a strip of metal having the longitudinal edge portions thereof folded along lines extending longitudinally of the strip toward the body of the strip and then folded outwardly to extend substantially at right angles to the body of the strip, said outwardly turned longitudinal edge portions being serrated to provide pointed projections, the body of the strip being convexly curved in cross section between the lines of folding of said longitudinal edge portions, and a filler member disposed between the inner face of said body of the strip and the adjacent faces of said folded portions of the strip.

2. A metal binding strip formed of a strip of metal having a longitudinal edge portion thereof folded along a line extending longitudinally of the strip toward the body of the strip and then folded outwardly to extend substantially at right angles to the body of the strip, said outwardly turned longitudinal edge portion being serrated to provide pointed projections, and a filler member

disposed between the inner face of said body of the strip and then folded outwardly to of the strip and the folded portion of the extend substantially at right angles to the strip. body of the strip, said outwardly turned 10 longitudinal edge portions being serrated to provide pointed projections.

3. A metal binding strip formed of a strip of metal having the longitudinal edge portion thereof folded along lines extending longitudinally of the strip toward the body

FRANK DE WITTE JACOBS.
